UNITED STATES PATENT OFFICE.

WALDEMAR CARL AXEL PETERSEN, OF COPENHAGEN, DENMARK, ASSIGNOR TO
BLYANTFABRIKEN VIKING, LIMITED LIABILITY COMPANY, OF COPENHAGEN,
DENMARK, A CORPORATION.

RECEPTACLE FOR WRITING LEADS, NEEDLES, AND LIKE ARTICLES.

Application filed March 23, 1926, Serial No. 96,848, and in Denmark March 30, 1925.

This invention is for improvements in or relating to receptacles for small shaped articles, and more particularly to a simple and efficient way of manufacturing the same from springy sheet metal. The receptacle according to the present invention can easily be opened for filling and emptied by pressure applied by the finger. The receptacle can be made from a single stamped metal blank, such as tin plate, and automatically closed in such a manner that the objects enclosed within the same are prevented from falling out accidentally. The special manner of manufacture renders it possible to use special tools so that the manual work is reduced to a minimum and keep the cost of producing the receptacle very low.

The present invention consists of a receptacle for writing leads, needles and like articles which comprises two box shaped members yieldingly connected to one another and adapted to telescope one within the other in such a manner that openings located in the adjacent end walls of the said members are normally out of register but may be brought into register by pressing of said members into the other.

The invention is more particularly described with reference to the accompanying drawings in which:

Figure 1 illustrates a sheet metal blank from which the receptacle is formed,

Figure 2 illustrates the final shaping operation to which the blank is subjected,

Figure 3 is a longitudinal section of the completed receptacle in closed condition,

Figure 4 is a cross section on the line A

B of Figure 3, and

Figure 5 is a perspective view of the receptacle in closed condition.

Referring to the drawings, the receptacle consists of two resiliently connected box shaped members one of which is adapted to telescope within the other, which are provided with a common end wall which also constitutes the resilient connection between the members.

For producing a receptacle according to

the present invention a blank *a* of the form shown in Figure 1 and having an opening *b* is first stamped. The blank *a* is bent at a right angle along the lines *c* whereby two trough shaped members, *d* and *e* connected by a resilient metal strip *f* are formed. The member *e* is made a little narrower than the member *d* so as to enable the member *e* to be accommodated in the member *d* when they are bent along the lines *g*. Likewise the flaps *h* and *k* are bent in a right angle so that the flap *h* closes part of the end of the box member *e* as it appears in Figure 3. The flaps *m* and *n* form a part which can be bent as a whole along the line *n*, as indicated in Figure 2, whereby the finished receptacle shown in Figure 5 is produced. The flap *k* comes below the bottom of the member *e* and forms a stop for the same limiting the distance through which the member *e* can be moved in an outward direction owing to the resilient strip *f* which forms a common end wall to the box shaped members *d* and *e*.

The side walls of the member *d* are provided with small cut away portions *o* which render it easy to push the member *e* into the member *d*.

When the members of the receptacle are in their normal positions the opening *b* is closed by the flap *h* in the manner indicated in Figure 3, so that the articles are prevented from falling out through the said opening. If it is desired to take one or more articles from the receptacle the same is held in a slanting position as indicated in Figure 3, and the member *e* is pressed into the member *d*, so that the bottom of the member *e* lies flush with the lower edge of the opening *b* so that the articles may slide out under the flap *h* through the opening *b*. The receptacle may be filled by means of the same operation.

Having thus fully described my invention I claim as new and desire to secure by Letters Patent:

A receptacle for writing leads, needles and the like articles, comprising two box

shaped members pressed from a single blank and yieldingly connected to one another the back wall of each member being formed from the resilient strip connecting the parts 5 of the said blank from which each member is pressed, the said members being adapted to telescope one within the other, adjacent end walls of the said members having openings normally out of register but adapted to be brought into register by pressing one of 10 said members into the other.

In testimony whereof I have affixed my signature.

WALDEMAR CARL AXEL PETERSEN.
